DESIGN.

W. A. SCHULER.

FASTENER.

APPLICATION FILED JULY 2, 1919.

54,961.

Patented Apr. 20, 1920.

Proprietor:

William A. Schuler

UNITED STATES PATENT OFFICE.

WILLIAM ANTON SCHULER, OF NEW YORK, N. Y.

DESIGN FOR A FASTENER.

54,961.

Specification for Design.

Patented Apr. 20, 1920.

Application filed July 2, 1919. Serial No. 308,337. Term of patent 14 years.

To all whom it may concern:

Be it known that I, WILLIAM ANTON SCHULER, a citizen of the United States, and residing at New York, in the county of New York and State of New York, have invented a new, original, and ornamental Design for Fasteners, of which the following is a specification, reference being had to the accompanying drawing, forming part thereof.

The figure is a perspective view of a fastener, showing my new design.

I claim:

The ornamental design for a fastener, as shown.

In witness whereof, I hereunto subscribe my name this 28th day of June, A. D., 1919.

WILLIAM ANTON SCHULER.

Witnesses:

F. W. BURR,
GEO. W. HEALEY.
